[57] CLAIM

The ornamental design for a glove, as shown and described.

DESCRIPTION

FIG. 1 is a left side elevational view of a glove showing my new design;

FIG. 2 is a top plan view thereof;

FIG. 3 is a right side elevational view thereof;

FIG. 4 is a bottom plan view thereof;

FIG. 5 is a front elevational view thereof; and

FIG. 6 is a rear elevational view thereof.

The broken lines on the glove indicate stitching.
